DESIGN FOR A HEAD GUARD FOR AN ELECTRIC DRY SHAVER

Harry E. Upham, Bridgeport, Conn.

Application November 6, 1942, Serial No. 108,712

Term of patent 7 years

To all whom it may concern:

Be it known that I, Harry E. Upham, a citizen of the United States, residing at 53 Eaton Street, Bridgeport, in the county of Fairfield and State of Connecticut, have invented a new, original, and ornamental Design for a Head Guard for an Electric Dry Shaver, of which the following is a specification, reference being had to the accompanying drawing forming part thereof.

Fig. 1 is a perspective of the head guard showing my new design.

Fig. 2 is a top plan view of the head guard.
Fig. 3 is a bottom plan view of the head guard.
Fig. 4 is an end elevation of the head guard,
and

Fig. 5 is a side elevation of the head guard.

I claim:

The ornamental design for a head guard for an electric dry shaver, as shown.

HARRY E. UPHAM.
